UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

LOOPER-THREAD CONTROLLER.

1,216,738.

Specification of Letters Patent.

Patented Feb. 20, 1917.

Application filed November 5, 1910. Serial No. 590,916.

To all whom it may concern:

Be it known that I, DUDLEY S. SEYMOUR, a citizen of the United States, residing at Oak Park, in the county of Cook, State of Illinois, have invented certain new and useful Improvements in Looper-Thread Controllers, of which the following is a description, reference being had to the accompanying drawing and to the letters and figures 10 of reference marked thereon.

The invention relates to new and useful improvements in thread controllers, and more especially to thread controllers used in connection with a thread carrying looper. 15 An object of the invention is to provide a thread controlling mechanism which shall positively take care of the thread during the movements of the looper, taking up and releasing the thread as required in order to 20 avoid the skipping of stitches and to assist in making a comparatively tight stitch.

In the drawings which show by way of illustration one embodiment of the invention;

25 Figure 1 is a sectional view through the casing, showing the cover plate removed, and the looper and thread controlling mechanism in plan view.

Fig. 2 is a longitudinal section through 30 the machine.

Fig. 3 is a view of the forward end of the machine, showing the looper in side elevation.

Fig. 4 is a detail partly in section, showing the pull-off and one of the thread guides therefor.

Fig. 5 is a view partly in section, showing the take-up for the looper thread at the extreme rearward movement.

40 Fig. 6 is a detail partly in section, showing the thread clamped, and the clamp for operating the same.

Fig. 7 is a view similar to Fig. 6, showing the take-up member at the forward end 45 of its stroke.

The machine as herein shown, consists of a bed plate 1 from which rises a standard 2 carrying a cylindrical work support 3. The looper 4 is of the usual thread carrying 50 type, and is mounted on the end of a shaft 5 mounted in bearings in the frame of the machine. The looper 4 as herein shown, cooperates with two needles 6 and 7. The looper supporting shaft 5 is oscillated

by a crank arm 8, which is connected to a link 9 which may be reciprocated in any desired way.

The looper supporting shaft is moved endwise in order to give the looper a needle avoiding movement by means of a sleeve 10, which is mounted between spaced collars rigidly secured to the looper supporting shaft. The sleeve 10 carries a downwardly projecting arm 11, which is connected by a link 12, with a rock shaft 13. The rock 65 shaft 13 carries an arm 14, which is connected to a link 15 that may be reciprocated in any desired way. The sleeve 10 is held from oscillation with the looper by means of the guide 16, which may be secured to the frame 70 in any desired way.

The take-up 17 is carried by a sleeve 18 (see Fig. 5) which is rigidly mounted on the looper supporting shaft 5. This take-up has a forwardly projecting nose 19 and 75 a laterally projecting cam-shaped shoulder 20. The take-up member 17 vibrates between spaced thread guides 21 and 22 (see Fig. 1).

A pull-off arm 23 is carried by a collar 24 80 rigidly secured to the looper supporting shaft 5. This arm 23 is mounted to oscillate between thread guides 25 and 26. Located between the pull-off and the take-up for the looper thread, is a thread clamp consisting of spring members 27 and 28. These gripping members 27 and 28 are secured to a bracket 29 carried by the frame of the machine by a screw 30. A cam 31 carried by the looper supporting shaft 5, is provided with a flat side 32 so that when the looper supporting shaft is in the position shown in Fig. 5, the flat portion 32 of the cam is adjacent the spring clamping member 28, and the clamping members 27 and 28 95 may be opened.

When the looper supporting shaft is oscillated, the cam 31 will engage the member 28 and positively clamp the thread between the clamping members 27 and 28. As a 100 further means for opening the thread clamps to release the thread, I have mounted on the sleeve 10 a plate 33 which carries an arm 34 having a laterally projecting cam faced finger 35 (see Fig. 1). This arm 34 reciprocates back and forth with the looper supporting shaft, and will be brought into engagement with a cam shoulder 36 carried by

the clamping member 27. This movement of the frame 34 through the finger 35 will crowd the clamping member 27 away from the clamping member 28, and entirely release 5 the thread from all clamping action.

10 The thread is led from the supply through a tension 37 and thence through the thread guides 25 and 26 of the pull-off between the clamping members 27 and 28, then through the thread guides 21 and 22 to the take-up. The thread is then led through a thread guide 38 underneath guiding pins 39 and 40 and through an opening 41, to the looper. A bracket 42 at the forward end of the opening 21 is provided with a curved face for 15 guiding the looper thread to the looper.

20 In the operation of my device, when the looper is at the forward end of its stroke, the take-up is in the position shown in Fig. 5. The needles at this time are also at the upper end of their stroke. As the looper shaft oscillates to retract the looper, the take-up is moved into contact with the looper thread, taking up all slack in the looper 25 thread, and drawing the thread between the thread, and drawing the thread between the eye of the looper and the material taut, so as to allow the needles to pass between this portion of the looper thread and the body of the looper.

30 As soon as the points of the needles are well below the needle thread, the looper thread slips off from the cam shoulder on the take-up and is entirely released so that slack looper thread is given to the looper 35 after the previous needle loops are shed from the looper, so that said needle loops may be run up close to the under surface of the material, while the looper thread is free from strain.

40 When the looper is at the rear end of its stroke, the take-up is in the position shown in Fig. 7, that is, with the looper thread at the extreme end of the cam shoulder on the under side of the take-up. As the looper 45 starts forward, the cam shoulder will again engage the thread, taking up a portion of the slack before the thread slips over the cam shoulder, and is released.

45 During the forward movement of the take-up, the looper is being retracted and is therefore, at its extreme left as viewed in Fig. 1. The arm 34 controlling the thread clamp, is therefore, in such position as to release the clamping members 27 and 28, and 55 allow the thread to be gripped during the entire forward movement of the take-up. The entire action of the take-up therefore, at this time is upon the looper thread between the thread clamp and the looper. As the 60 take-up starts to retract, the looper is moving forward and has moved to its extreme right hand position, as viewed in Fig. 1, and the arm 34, through the cam finger 25, opens the thread clamps so that thread may be 65 drawn therefrom to the pull-off.

When the take-up is moving forward and the thread clamps are closed, the pull-off arm 23 is also moving upward as viewed in Fig. 4, and the thread is engaged between the thread eyes 25 and 26 and pulled through the tension 37. It will thus be seen that I have provided a pull-off for pulling thread through the tension from the supply, and a take-up for controlling the looper thread between the pull-off and the looper, and also a 70 thread clamp which is located between the looper and pull-off and which operates to clamp the thread at the proper time so that the action of the pull-off and the take-up on the looper thread are substantially independent of each other.

75 The take-up which I have constructed is especially adapted for a machine having a cylindrical bed plate or work support, as its field of operation is extremely small. The 80 essential features of the take-up member consist in the shank portion which is secured to the looper shaft and the overhanging portion which is formed with the concentric surface which allows it to move very close 85 to the bracket supporting the thread guides and the concentric under surface which retains the thread in proper relation to the take-up member, and the projecting cam surface which takes up and releases the thread 90 during each oscillation of the take-up member.

95 It will be obvious that minor changes in the details of construction may be made without departing from the spirit of my invention.

Having thus particularly described my invention, what I claim as new and desire to secure by Letters Patent, is:—

10 1. A thread controller including in combination, thread guides, a take-up member comprising an overhanging arm having a thread engaging cam projecting from its inner face which takes up and releases thread 1 during each oscillation of the take-up member.

11 2. A thread controller including in combination, thread guides, a pivoted take up member comprising an overhanging arm, having a concentric surface on its under face 1 whereby the thread is retained in proper relation to the take-up member, and a cam surface for engaging the thread.

12 3. A thread controller including in combination, thread guides, a pivoted take-up member comprising an overhanging arm, the outer face of which is substantially concentric whereby it may operate in a small space and the inner face of which has a projecting cam thread engaging surface.

13 4. A thread controller for sewing machines, comprising a shank adapted to be attached to an oscillating member, and an overhanging arm, said overhanging arm having a concentric outer surface whereby it

- may operate in a small space, and a cam projecting thread engaging surface on its inner face.
5. A thread controller comprising a shank adapted to be attached to an oscillating member, and an overhanging arm, said overhanging arm having a concentric outer surface whereby it may operate in a small space, and a concentric inner surface at its free end whereby the thread is retained in proper relation to the take-up member, and a projecting inner surface for engaging the thread.
10. A sewing machine including in combination, a looper-supporting shaft, a looper mounted thereon, a take-up member carried by said looper-supporting shaft, said member comprising an overhanging arm having a thread-engaging cam projecting therefrom, thread guides between which said take-up member operates, a thread-clamping device between said take-up member and the supply, and a cam carried by the looper shaft for causing the clamping device to clamp the looper thread.
15. A thread controller including in combination, thread guides, an oscillating shaft, a take-up member secured to said oscillating shaft and adapted to oscillate between said thread guides, said take-up member comprising an overhanging arm cut away on its under surface, said guides being so disposed relative to the take-up member that the thread passing through the thread guides and underneath the overhanging arm, will be substantially straight at the extremes of oscillation of the take-up member, and a projecting cam portion for engaging the thread and taking up and releasing the same during the oscillation of said take-up member.
20. A thread controller including in combination, an oscillating shaft, a take-up member mounted on said oscillating shaft, thread guides between which said take-up member oscillates, said take-up member having a cut away portion between its outer surface and said oscillating shaft through which the thread is adapted to pass from one thread guide to another, said cut away portion including a projecting cam for engaging and taking up and releasing the thread during the oscillation of the take-up member.
25. The combination of a looper shaft, means for oscillating said looper shaft and moving the same endwise, a looper carried thereby, a take-up for the looper thread including an overhanging take-up arm mounted on said looper shaft, and oscillating therewith, thread guides arranged on each side of said take-up member, said take-up member having a concentric outer surface, a part of the under face of said overhanging arm being concentric, and a thread cam shaped for taking up and releasing the thread during the oscillation of said take-up member.
30. A sewing machine including in combination, a looper-supporting shaft, a looper mounted thereon, a take-up member carried by said looper-supporting shaft, said member comprising an overhanging arm having a thread-engaging cam projecting therefrom, thread guides between which said take-up member operates, and a thread-clamping device between said take-up member and the supply, a cam carried by the looper shaft for causing the thread-clamping device to clamp the looper thread, and means carried by the looper shaft for engaging and separating the clamping members of the clamping device.
35. A sewing machine including in combination, a looper-supporting shaft, a looper, a thread-controlling device for the looper thread comprising a take-up, and thread-clamping members, a cam carried by the looper shaft for causing said members to clamp the thread when the shaft is oscillated, and a member carried by said looper shaft for separating the clamping members when the looper shaft is moved longitudinally.
40. A thread clamp consisting of yielding members, a cam for closing said members, and independent means for positively separating said members.
45. A thread clamp consisting of resilient members, a cam for engaging said resilient members for causing the same to clamp the thread, means for oscillating the cam, whereby said members are caused to be released, and a second cam for positively separating said members to release the thread.
50. In a sewing machine, having stitch forming mechanism including an oscillating and reciprocating looper shaft, a take-up member having a shank portion secured to the looper shaft, thread guides, a bracket supporting the same, said take-up member having an overhanging portion formed with a concentric upper surface located and moving close to the bracket supporting the thread guides and having a concentric under surface which retains the thread in proper relation to the take-up member, and having a projecting cam surface which takes up and releases the thread during each oscillation of the take-up member.
55. A sewing machine including in combination, a looper-supporting shaft, a looper mounted thereon, a take-up member carried by said looper-supporting shaft, said member comprising an overhanging arm having a thread-engaging cam projecting therefrom, thread guides between which said take-up member operates, and a thread-clamping device between said take-up member and the supply, said clamping device being controlled by the movements of the looper shaft.
60. A sewing machine including in combination, a looper-supporting shaft, a looper mounted thereon, a take-up member carried by said looper-supporting shaft, said member comprising an overhanging arm having a thread-engaging cam projecting therefrom, thread guides between which said take-up member operates, a thread-clamping device between said take-up member and the supply, and a cam carried by the looper shaft for causing the clamping device to clamp the looper thread.
65. A sewing machine including in combination, a looper-supporting shaft, a looper mounted thereon, a take-up member carried by said looper-supporting shaft, said member comprising an overhanging arm having a thread-engaging cam projecting therefrom, thread guides between which said take-up member operates, and a thread-clamping device between said take-up member and the supply, a cam carried by the looper shaft for causing the thread-clamping device to clamp the looper thread, and means carried by the looper shaft for engaging and separating the clamping members of the clamping device.
70. A sewing machine including in combination, a looper-supporting shaft, a looper, a thread-controlling device for the looper thread comprising a take-up, and thread-clamping members, a cam carried by the looper shaft for causing said members to clamp the thread when the shaft is oscillated, and a member carried by said looper shaft for separating the clamping members when the looper shaft is moved longitudinally.
75. A sewing machine including in combination, a looper-supporting shaft, a looper, a thread-controlling device for the looper thread comprising a take-up, and thread-clamping members, a cam carried by the looper shaft for causing said members to clamp the thread when the shaft is oscillated, and a member carried by said looper shaft for separating the clamping members when the looper shaft is moved longitudinally.
80. A thread clamp consisting of resilient members, a cam for engaging said resilient members for causing the same to clamp the thread, means for oscillating the cam, whereby said members are caused to be released, and a second cam for positively separating said members to release the thread.
85. A thread clamp consisting of yielding members, a cam for closing said members, and independent means for positively separating said members.
90. A thread clamp consisting of resilient members, a cam for engaging said resilient members for causing the same to clamp the thread, means for oscillating the cam, whereby said members are caused to be released, and a second cam for positively separating said members to release the thread.
95. A thread clamp consisting of resilient members, a cam for engaging said resilient members for causing the same to clamp the thread, means for oscillating the cam, whereby said members are caused to be released, and a second cam for positively separating said members to release the thread.
100. A thread clamp consisting of yielding members, a cam for closing said members, and independent means for positively separating said members.
105. A thread clamp consisting of resilient members, a cam for engaging said resilient members for causing the same to clamp the thread, means for oscillating the cam, whereby said members are caused to be released, and a second cam for positively separating said members to release the thread.
110. A thread clamp consisting of resilient members, a cam for engaging said resilient members for causing the same to clamp the thread, means for oscillating the cam, whereby said members are caused to be released, and a second cam for positively separating said members to release the thread.
115. A thread clamp consisting of yielding members, a cam for closing said members, and independent means for positively separating said members.
120. A thread clamp consisting of resilient members, a cam for engaging said resilient members for causing the same to clamp the thread, means for oscillating the cam, whereby said members are caused to be released, and a second cam for positively separating said members to release the thread.
125. A thread clamp consisting of yielding members, a cam for closing said members, and independent means for positively separating said members.
130. A thread clamp consisting of resilient members, a cam for engaging said resilient members for causing the same to clamp the thread, means for oscillating the cam, whereby said members are caused to be released, and a second cam for positively separating said members to release the thread.

- nation a standard, a cylindrical work support extending from said standard, a looper shaft mounted in said work support, a looper operated by said shaft, means for oscillating 5 said looper shaft, and a looper thread controlling mechanism located in said work support, said mechanism including an oscillating member mounted on and movable with said looper shaft, and thread guides 10 for holding the looper thread in operative engagement with said oscillating member.
17. A sewing machine including in combination a standard, a cylindrical work support extending from said standard, a looper shaft mounted in said work support, a looper operated by said shaft, means for oscillating 15 said looper shaft, and a looper thread controlling mechanism located in said work support, said mechanism including an oscillating member mounted on and movable with said looper shaft, and thread guides for holding the looper thread in operative engagement with said oscillating member.
- trolling mechanism located in said work support, said mechanism including an oscillating member mounted on and movable with 20 said looper shaft, and thread guides for holding the looper thread in operative engagement with said oscillating member, said oscillating member having a cam shaped thread engaging surface which takes up 21 and releases thread during the movement of said member in each direction.

In testimony whereof I affix my signature, in presence of two witnesses.
